UNITED STATES PATENT OFFICE

2,346,886

OIL FLOAT OPERATED SWITCH

Walter W. Williams, Bloomington, Ill.

Application June 27, 1941, Serial No. 400,077

9 Claims. (Cl. 62—115)

This invention relates to refrigerating units, with particular reference to units including a compressor and oil separator, rectifier or sump and wherein the unit employs a refrigerant appreciably soluble in the compressor lubricant. In the present embodiment, the compressor is of the piston type and operates intermittently to maintain a predetermined range of temperatures in the evaporator. The compressor is idle during the "off" portion of the cycle, and at such times the pressure in the crankcase rises due to the increasing temperature of the evaporator.

During the building up of the pressure in the crankcase, the refrigerant vapors returning from the evaporator dissolve to a material extent in the lubricant in the crankcase, and this lubricant and dissolved refrigerant therein drain into a sump or chamber below the crankcase. The pressure outlet conduit from the compressor extends through the oil in the sump, and the high temperature of this conduit will heat the lubricant sufficiently to expel the major portion of the dissolved vapors which have been carried into the sump with the lubricant.

In operating the compressor, it is of course necessary to retain at all times a sufficient quantity of lubricant in the sump to properly lubricate the mechanism. Furthermore, it is desirable that the level of the lubricant in the sump should never be below the refrigerant conduit passing therethrough, as otherwise the lubricant may not be sufficiently heated to vaporize the refrigerant dissolved therein.

It is, therefore, an object of the present invention to provide an automatic means which will make the motor and associated temperature control ineffective to operate the compressor except when the lubricant level is at a predetermined height relative to the refrigerant conduit in the sump.

A further object is to provide a lubricant and refrigerant control which will be effective to prevent operation of the unit except when the lubricant and lubricant heating means are in a predetermined relationship adapted to produce effective vaporizing of dissolved refrigerant and efficient lubrication of the mechanism.

Further objects will be apparent from the specification and the appended claims.

In the drawing:

Fig. 1 is a side elevation partially in section of the compressor forming a part of the usual refrigerating system.

Fig. 2 is a diagrammatic view illustrating the electrical control circuit, including the usual low

pressure control switch, the motor, and the lubricant level control element in cooperative relation to simultaneously control the refrigerating unit and the lubricant level associated therewith.

5 Fig. 3 is a top view of the electrical control switch illustrated in Fig. 1.

The embodiment illustrated comprises a well known type of multiple piston compressor having cylinders 1, a crankcase 2, and the usual connecting rods 3 in driven relation with a crankshaft 4 having a pulley 5 secured thereto whereby the compressor may be driven by the usual electric motor as illustrated in Fig. 2. A sump 6 is positioned below the crankcase 2 and may comprise an elongated chamber substantially as illustrated.

A drainpipe 7 leads from the crankcase into the sump 6, whereby lubricant from the crankcase 2 may drain into the sump. A conduit 8 leads from the bottom of the sump 6 to an oil pump 9, the latter being mounted on the casing 2 and operatively connected to the crankshaft. The oil pump 9 withdraws lubricant from the bottom of the sump 6 and forces it through suitable conduits to the various bearing surfaces of the compressor. A constant circulation of lubricant to the bearings is thereby provided when the compressor is in operation. The lubricant, after passing through the bearings, drains downwardly from the crankcase 2 through the drainpipe 7 and into the sump 6, and the refrigerant vapors expelled from the surface of the lubricant in the sump 6 may pass upward through the drainpipe 7 into the crankcase 2 and be drawn by the pistons into the compression cylinders, while at the same time 35 the substantially pure lubricant at the bottom of the sump 6 is circulated through the working parts of the compressor by means of the pump 9. Also, if desired, a conduit 10 may be provided leading from the top of the sump 6 to the top of the crankcase 2, through which the refrigerant vapors expelled from the lubricant may be conducted to the upper part of the crankcase 2 closely adjacent the cylinders.

In order to heat the lubricant in the sump 6, 45 the compressor outlet conduit 11 leads from the top of the cylinders 1 to the sump 6 and a portion 11a of this conduit 11 extends preferably horizontally through the sump 6 in a position to be submerged in, or at least sufficiently in contact with, the lubricant to cause vaporization of the dissolved refrigerant. In operation, the level 21 of the body of lubricant in the sump is preferably materially above the conduit 11a. Therefore, the lubricant will be heated sufficiently to expel the 55 dissolved refrigerant vapors from the lubricant.

In order to maintain at all times a sufficient amount of lubricant in the sump 6 to contact the necessary area of the heating conduit 11a so that the lubricant will maintain the required temperature, a float operated switch is provided for making ineffective the operation of the usual motor and the usual pressure controlled switch associated therewith, when the lubricant in the sump 6 reaches a predetermined minimum low level. The float operated switch comprises a float 12 mounted on the end of a short arm 13, the arm being pivoted at 14 on a bracket 15 secured to the end wall of the sump. A mercury switch 16 of well known type is supported on the float 12 and arm 13, as shown in Fig. 3, and is tiltable in response to movement of the float in accordance with variations in the lubricant level. The positioning of the switch 16 may be adjusted by an adjusting screw 14a. The switch 16 is connected in series with and between a motor 17 and a pressure control switch 18 in a power circuit 19, as illustrated in Fig. 2, the power circuit being initially controllable by means of a main switch 20. When the lubricant level 21 is above the level indicated by the dotted line 21a in Fig. 1, the mercury switch 16 will be retained in "on" position so that the unit may operate in the usual manner under the control of the low pressure switch 18, and when the lubricant reaches a predetermined low level, such for instance as indicated by the dotted line 21a, the float switch will then be positioned to break the motor circuit and the motor will not operate in response to action of the low pressure control switch 18 until more lubricant has been introduced into the sump 6.

To prevent adversely affecting the mercury switch 16 by variations in temperature and pressure, the float 12 is provided on its upper side with a small vent conduit 12a.

It is intended, of course, that the invention should not be limited to the specific embodiment or embodiments disclosed herein, since modifications may be made, and it is contemplated, therefore, by the appended claims to cover any such modifications as fall within the true spirit and scope of this invention.

Having thus described this invention, what is claimed and desired to be secured by Letters Patent is:

1. In a sealed refrigerating system including a compressor having a crankcase and lubricant reservoir therefor forming a part of said sealed system, means for circulating lubricant from said reservoir through the operating mechanism of said compressor and returning the said lubricant to said reservoir, a motor for operating said compressor, means operable by refrigerant pressure in said system to cause intermittent operation of said motor, and additional means controlled by the lubricant level in said reservoir to make said motor ineffective to operate said compressor when the lubricant level in said reservoir is at or below a predetermined level.

2. In a sealed refrigerating system including a compressor having a crankcase forming a part of said sealed system, an oil supply for said compressor, a motor for operating said compressor, and means dependent upon the amount of oil in said supply for causing intermittent operation of said compressor in response to fluctuations in the pressure in said system.

3. In a sealed refrigerating system including a compressor forming a part of said sealed system, a lubricant supply communicating with said compressor, a heater in said lubricant supply and de-

pendent on the lubricant level for effective vaporizing of dissolved refrigerant in said lubricant, and means controlled by the lubricant level to cause intermittent operation of said compressor in response to variations in pressure in said system and to prevent operation when the relationship between said lubricant and said heater become ineffective for proper vaporization of said dissolved refrigerant.

4. In a sealed refrigerating system including a compressor having a crankcase and lubricant reservoir therefor forming a part of said sealed system, means for circulating lubricant from said reservoir through the operating mechanism of said compressor and returning the said lubricant to said reservoir, a motor for operating said compressor, a low pressure control means associated with said motor and said sealed system for controlling said motor in accordance with variations in pressure in said sealed system, and float operated means in said reservoir for making said motor ineffective for normal operation when the lubricant in said reservoir is below the predetermined level.

5. In a sealed refrigerating system including a compressor having a crankcase and lubricant reservoir therefor forming a part of said sealed system, means for circulating lubricant from said reservoir through the operating mechanism of said compressor and returning the said lubricant to said reservoir, an electric motor for operating said compressor, a low pressure control means associated with said motor and said sealed system for controlling said motor in accordance with variations in pressure in said sealed system, float operated means in said reservoir for making said motor ineffective for normal operation when the lubricant in said reservoir is below a predetermined level, and heating means in said reservoir extending at least partially below said predetermined level.

30 6. In a sealed refrigerating system including a compressor having a crankcase and lubricant reservoir therefor forming a part of said sealed system, means for circulating lubricant from said reservoir through the operating mechanism of said compressor and returning the said lubricant to said reservoir, an electric motor for operating said compressor, an electrical circuit for said motor, a switch controlled by the pressure in said system for alternatively making and breaking said circuit, and means controlled by the level of said lubricant to control the effectiveness of said circuit.

55 7. The combination with a sealed refrigerating system including a compressor having the usual crankcase as a part of said sealed system, a pressure lubricating system for said compressor and a separate sealed sump below said crankcase and having one or more conduit connections therewith for oil drainage to said sump and gas return to said refrigerating system, and a high pressure refrigerant conduit in said sump in heat transfer contact with said lubricant, of a motor for operating said compressor, a motor circuit, a normally closed switch in said circuit, and a float in said sump arranged to open said switch when the lubricant falls below a predetermined level relative to said conduit.

60 8. The combination with a sealed refrigerating system including a compressor, a lubricant sump, and a pump for circulating said lubricant through said compressor and said sump, of an electric motor for operating said compressor, an automatic low pressure control switch for the motor

70

circuit, a float operated switch in said sump, said float switch being automatically operable to make said motor and control switch ineffective to operate said system when the lubricant in said sump falls below a predetermined level.

9. In a sealed refrigerating system including a compressor having a crankcase and lubricant reservoir therefor forming a part of said sealed system, means for circulating lubricant from said reservoir through the operating mechanism of said compressor and returning the said lubricant to said reservoir, a high pressure refrigerant con-

duit in said reservoir in heat transfer contact with said lubricant for vaporizing refrigerant dissolved within said lubricant prior to circulation thereof through said operating mechanism, and 5 means controlled by the lubricant level in said reservoir for causing intermittent operation of said compressor, said conduit being positioned within said reservoir so as to be at all times at least partially immersed in the lubricant while 10 said compressor is operating.

WALTER W. WILLIAMS.
